MEANS FOR CONTROLLING THE STARTING
OF INTERNAL COMBUSTION ENGINESRoy G. Fulcher and William T. Carle, Chicago,
Ill., assignors to Mary Baker Fulcher, Chicago,
Ill.

Application February 4, 1937, Serial No. 123,968

5 Claims. (Cl. 290—38)

This invention relates to improvements in means for controlling the starting of internal combustion engines and it consists of the matters hereinafter described and more particularly 5 pointed out in the appended claims.

The means above mentioned, with which the present invention is more particularly concerned, is of the kind illustrated in United States Letters Patent 1,912,669 granted to Herbert Horatio 10 Traill on June 6, 1933.

The means in said patent has certain objections which the present invention seeks to overcome and among said objections mentioned is the cost of the parts going therewith, the non-positiveness of starting the engine with a resulting 15 battery drainage, and the requirement of a considerable amount of switch movement in manipulating the same, making it somewhat difficult for use by inexperienced persons with the possibility 20 of getting out of order.

Among the objects of the present invention is to provide a means of this kind which is more simple in construction and is, therefore, more economical to produce, is more positive in its engine starting operations and requires less switch 25 movement so as to be easy to manipulate by inexperienced persons and is not apt to get out of order.

The above mentioned objects of the invention, 30 as well as others, together with the advantages thereof will more fully appear as the specification proceeds.

In the drawing:

Fig. 1 is a diagrammatic view illustrating the 35 preferred form of the invention.

Figs. 2 and 3 are diagrammatic views illustrating the positions of parts of a switch forming a part of the invention, when said switch is in the full "on" and in the "running" positions.

Fig. 4 is a view illustrating a modified form of 40 the invention.

Referring now in detail to that embodiment of the invention illustrated in Figs. 1 to 3 inclusive of the accompanying drawing, 10 indicates an electric starting motor, now conventional in automotive vehicles for starting the engines thereof. As shown herein, the motor is provided at one end with a hollow housing 11 and one end of the armature shaft 12 of said motor is journaled in the end wall of the housing. A portion 45 of the shaft within the housing is formed with helical ribs or splines 13 and on said portion of said shaft is mounted a pinion 14. The pinion is adapted for a rotative as well as an axial movement on the shaft 12, into and out of operative engagement with the ring gear on the fly wheel of the engine (not shown) with which it is associated for starting purposes.

On the inner end of said pinion is provided a 50 radial flange 15 having a smooth rounded periph-

ery. A longitudinally extending spring contact finger 16 is secured along one end to the inner surface of the housing in a manner whereby it is insulated therefrom. The other end of said finger is so formed that when the pinion travels axially outward on the shaft, the flange 15 engages and makes a suitable contact therewith. The housing mentioned may be grounded as at 17 to any convenient part of the associated vehicle.

18 indicates an electromagnet associated with the motor for controlling the passage of electric current to the motor whereby the same is energized and deenergized. As herein shown, said magnet includes a casing 19 enclosing a coil 20 and an associated core 21 which is spring-pressed 15 in one direction. This core carries a bridge piece 22 at one end. When the coil is energized, it causes the core to move outwardly and into engagement with a pair of contacts 23 and 24, secured in one end of the casing, so as to electrically 20 connect the same together. One of said contacts is operatively connected to a terminal post 25 of the motor, while the other contact is arranged to have a conductor or line attached thereto and which will be referred to later. In the other end 25 of the casing is provided a pair of terminals 26 and 27 respectively for the coil of the electromagnet.

A manually operable switch 28 is associated with the means thus far described and said switch 30 may be in the form of a key actuated ignition lock as is now conventional in automotive vehicles. As herein shown, said switch includes a support 29 and a shaft 30 is arranged therein for a limited turning movement. This shaft carries a contact arm 31 electrically connected thereto and said shaft in turn is connected by a line 32 to one side of a battery 33, the other side of which is grounded. An arm 34 of insulation is secured to the arm 31, but is arranged in opposite 40 relation thereto. A contact finger 35 is carried on the free end of the insulation arm and a contact finger 36 is carried on the free end of the arm 31. The switch arms are adapted for a short turning movement clockwise from "off" through 45 the "running" position to a full "on" position, the return to "off" position being a counterclockwise movement. The switch arms normally stand in an "off" position up against a stop pin 37, a spring 37^a holding the arm in this position. 50

A relatively long arcuate contact 38 is fixed in the support 29 to the right hand side of the arm 31 when in the "off" position, and a pair of spaced spot contacts 39 and 40 respectively are fixed in the support 29 to the left hand side of 55 the switch arm 34 when in said "off" position. The contacts 39 and 40 are so arcuately spaced and the contact 38 is of such arcuate length that when the arms 31—34 are in the full "on" position, the contact finger 35 bridges the contacts 60

39 and 40 and the contact finger 36 engages the contact 38.

The contact 38 has a line 41 connected thereto and said line leads to the ignition system of the associated engine. A line 42 is provided between the line 41 and the terminal post 26 of the electromagnet 18. A line 43 connects the contact 39 with the other terminal post 27 of said electromagnet and the spring contact finger 16. 10 in the housing 11 of the motor is connected to the line 43 by another line 44. The contact 40 is grounded as at 45. The contact 23 of the electromagnet 18 is connected by a line 32^a to the line 32.

15 In the support 29 is provided a recess 46 which, when the switch is in the "running" position, is adapted to receive a yielding detent 47 on the switch arm 31. This detent and recess arrangement is such as to hold the switch arms 31—34 in "running" position against the action of the spring 37^a. A second stop pin 48 is provided in the support 29. This pin is adapted to be engaged by the arm 34 to limit the turning movement of said arm to the full "on" position.

20 The parts are shown in Fig. 1 in the "off" position. To start the associated engine, the switch arms 31 and 34 are swung to the full "on" position shown in Fig. 2 wherein the finger 36 of the arm 31 engages the contact 38 and the contact finger 35 bridges and engages both spot contacts 39 and 40. This connects the ignition system with the battery 33 through the contact 38, finger 36, arm 31, shaft 30 and line 32. Current also passes from the line 41 through line 25 42 to the terminal 26 of the electro-magnet 18, through the coil 20, terminal 27, line 43, contact 39, to contact 40 through the bridging contact finger 35 to the ground 45.

25 This energizes the coil 20 of the magnet 18 to cause a movement of the associated core 21 whereby its bridge piece 22 engages the contacts 23 and 24. Current then passes from the battery 33, through a part of line 32 to and through the line 32^a, the contact 23, bridge piece 22, contact 24 to the terminal post 25 of the starting motor 10 which is thus energized.

30 When the motor is energized, the armature shaft 12 is rotated and this causes the pinion to rotate and travel outwardly on the helical portion 13 of the shaft to engage the flywheel of the associated engine so as to crank the same. As the pinion moves outwardly on said helical portion of the shaft 12, its flange 15 engages the contact finger 16 to connect it to the ground 35 17 through parts of the motor 10.

35 It is apparent that when the switch 28 is in the full "on" position as shown in Fig. 2, two ground connections are provided for the electromagnet 18, one through the line 43, contact 39, 40 contact piece 35 and contact 40 and the other through the lines 43—44, finger 16, pinion 14 through the motor to ground 17.

40 After the switch 28 has been turned to its "on" position, it may be released so that it returns to the "running" position shown in Fig. 3 wherein the detent 47 engages in the recess 46 to hold it against the return action of the spring 37^a. At this time, the contact finger 35 has passed off the contact 40 but remains on the contact 39, 45 the contact finger 36 still engaging the contact 38. At this time the ignition is "on" and the electromagnet 18 is still operating to hold the motor circuit closed because the ground connection for the electromagnet is still being maintained through the lines 43—44, finger 16, pinion

14 and housing 11 to the ground 17. Thus, the ignition is "on" and the motor 10 is energized to crank and start the engine. When the engine is running under its own power, it drives the pinion 14 which moves inwardly on the helical portion 13 of the shaft 12, thus moving the pinion flange 15 out of engagement with the finger 16, thus breaking the circuit for the motor which becomes deenergized and stops.

50 In Fig. 4 we have illustrated a modified form of the invention and wherein the closing of the ignition circuit and the closing of one of the first ground connections for the electromagnet 18 may be carried out independently of each other. Thus, the switch structure may be reduced to the simplest and most economical form. As shown in Fig. 4, the parts associated with the ignition circuit are substantially the same as before and the contacts 39 and 40 which are the same as before, are electrically connected up in the same manner.

55 Instead of employing the contact finger 35 on an arm 34 which is movable with the arm 31, we mount said finger on a spring pressed plunger 34^a arranged in the support 29^a. This plunger 25 has a head 34^b arranged outside of the support 29^a in such a convenient location as to be operable by the thumb of the hand turning the switch arm 31. Said plunger also has a contact piece 35^a for engagement with the contacts 39 30 and 40.

35 In the operation of the structure above mentioned, when the switch arm 31 is turned to its full "on" position to engage the contact 38, the plunger 34^a may be depressed inwardly to cause 50 its contact piece 35^a to bridge and connect the contacts 39 and 40. This, not only energizes the ignition system, but it closes the circuit to the electromagnet 18, which in turn energizes the starting motor for engine cranking purposes. So 40 soon as the motor is energized, it establishes a second ground for the magnet 18 to hold the same closed, as before.

45 It is not necessary to retain the ground connection for the magnet 18 closed through the contacts 39—40 and piece 35^a. Therefore, so soon as the plunger is depressed after turning of the switch arm 31 to "on" position, the plunger may be released and the motor 10 remains energized so long as the engine requires cranking. 50 When the engine starts, it automatically breaks the circuit to the motor, which stops.

55 Should the motor be in operation to crank the engine and the engine refuse to start, due to some other faulty condition, a turning of the switch arm 31 back to "off" position breaks the circuit to the electromagnet 18 so that it breaks the circuit for the starting motor and said motor stops. The faulty condition of the engine may then be rectified and the procedure for again 60 starting the same is as before described. Should the spring 16 get out of order so as not to function as intended, this will not prevent engine starting operations because all that it would be necessary to do is to manually hold the switch 28 65 in the "on" position shown in Fig. 2 until the engine starts. When the engine has started, the switch is released and it will then return to the "running" position shown in Fig. 3.

70 With the arrangement described, a more positive starting of the engine is assured, a less expensive switch structure may be employed with more simple wiring and the amount of movement required for the arms 31—34 is reduced.

75 While in describing our invention, we have

referred in detail to the construction, form and arrangement of the parts involved, the same is to be considered only in the illustrative sense, so that we do not wish to be limited thereto except 5 as may be specifically set forth in the appended claims.

We claim as our invention:

1. In combination with an electric starting motor for an engine, an ignition circuit for said engine, a circuit for said starting motor, electromagnetic means for controlling said starting motor circuit, a third circuit capable of being grounded at a plurality of points so as to energize said electromagnetic means, means including a plurality of contacts manually movable into and adapted to be held in a position closing said ignition circuit and said third circuit respectively by grounding said third circuit at one of said points so as to energize said electromagnetic means 10 to close the circuit for the starting motor, means actuated by said motor when energized for grounding said third circuit at another of said points, said contacts when said manually operable means is released, operating automatically 15 to break said first mentioned ground connection, but to hold the ignition circuit closed, said starting motor, when driven by the started engine operating automatically to break said second ground connection made therethrough to open 20 said third circuit and deenergize said electromagnetic means.

2. In combination with an electric starting motor for an engine having an axially movable pinion, a circuit for said starting motor, an ignition circuit for said engine, electromagnetic means for controlling said starting motor circuit, a third circuit capable of being grounded at a plurality of points so as to energize said electromagnetic means to close the starting motor circuit, means 25 including a plurality of contacts manually movable into and adapted to be held in a position closing said ignition circuit and said third circuit respectively by grounding said third circuit at one of said points so as to close the circuit for the starting motor, means actuated by the axially 30 movable pinion when the starting motor has been energized for grounding said third circuit at another of said points, said contacts when said manually operable means is released, operating automatically to break said first mentioned ground connection, but to hold the ignition circuit closed, 35 said pinion, when driven by the started engine, operating upon said means actuated thereby to break said second ground connection made therethrough to open 40 said third circuit and deenergize said electromagnetic means.

3. In combination with an electric starting motor for an engine, an ignition circuit for said engine, a circuit for said starting motor, electromagnetic means for controlling said starting motor circuit, a third circuit capable of being grounded at a plurality of points so as to energize said electromagnetic means, to close the starting motor circuit, a switch including an ignition circuit contact, an electromagnetic means circuit contact and a ground contact constituting one of said grounded points for said third circuit, a switch arm associated with said contacts and movable in one direction from an "off" position, through a "running" position to a full "on" position and movable in the other direction back

to said "running" position, said switch arm when moved from said "off" position to the full "on" position, engaging the ignition contact, and said electromagnetic means contact and said ground contact respectively to connect the latter two contacts in circuit to close the ignition circuit and to ground said third circuit respectively through one of said points and thus energize said third circuit to cause said electromagnetic means to close the motor circuit and energize said starting 10 motor, means actuated by said starting motor when energized for grounding said third circuit at another of said points, said switch arm when released, automatically returning to said "running" position and moving out of engagement 15 with said ground contact to break the first mentioned ground connection but to hold the ignition circuit closed, said starting motor, when driven by the started engine operating automatically to break said second ground connection made therethrough to open said third circuit and deenergize 20 said electromagnetic means.

4. In combination with an electric starting motor for an engine, an ignition circuit for said engine, a circuit for the starting motor, electromagnetic means for controlling said starting motor circuit, a third circuit capable of being grounded at a plurality of points so as to energize said electromagnetic means, manually operable means for closing the ignition circuit and 25 for momentarily closing said third circuit by grounding the same at one of said points so as to energize said electromagnetic means to close said starting motor circuit, said manually operable means being formed for operation requiring 30 closing of the ignition circuit in order to complete said third circuit, means actuated by said motor when energized for grounding said third circuit at the other of said points before said first mentioned ground connection for said third 35 circuit is broken, said starting motor, when driven by the started engine operating automatically to break said second ground connection made therethrough to open said third circuit and deenergize 40 said electromagnetic means.

5. In combination with an electric starting motor for an engine, an ignition circuit for said engine, a circuit for said starting motor, electromagnetic means for controlling said starting motor circuit, a third circuit fed from the ignition 50 circuit and capable of being grounded at a plurality of points so as to energize said electromagnetic means, manually operable means for closing the ignition circuit and for closing said third circuit by grounding the same at one of said points 55 so as to energize said electromagnetic means to close the starting motor circuit, said manually operable means being formed for operation requiring closing of the ignition circuit in order to complete said third circuit, means actuated by said motor when energized for grounding 60 said third circuit at another of said points before said first mentioned ground connection for said third circuit is broken, said starting motor when driven by the started engine operating automatically to break said second ground connection made therethrough to open said third circuit and deenergize 65 said electromagnetic means.
